CLAIM

Apr. 1, 2021 (CN) 202130181519.5

The ornamental design for a holder accessory for portable electronic device, as shown and described.

(51) **LOC (14) Cl.** **14-03**

DESCRIPTION

(52) **U.S. Cl.**

FIG. 1 is a top, front, and right side perspective view of a holder accessory for portable electronic device, showing our new design;

USPC **D14/253**; D14/447

FIG. 2 is a bottom, rear, and left side perspective view thereof;

(58) **Field of Classification Search**

FIG. 3 is a front view thereof;

USPC D14/217, 251-253, 316, 385, 447, 452;

FIG. 4 is a rear view thereof;

D16/240, 242-244

FIG. 5 is a left side view thereof;

CPC G08B 13/1409; F16M 13/00; F16M

FIG. 6 is a right side view thereof;

2200/00; A45C 2011/002; A45C

FIG. 7 is a top view thereof; and,

2011/003; A47B 2023/049; A47B

FIG. 8 is a bottom view thereof.

2097/005; A47B 2097/006

The dash lines in the figures illustrate the portions of the design that form no part of the claimed design.

See application file for complete search history.

The dot-dash lines in the figures represent a boundary that forms no part of the claimed design.
